BINAURAL PROGRAM SYSTEM

Robert D. Duncan, Jr., East Orange, N. J., assignor to Wired Radio, Inc., New York, N. Y., a corporation of Delaware

Application February 11, 1936, Serial No. 63,461

4 Claims. (Cl. 179—1)

This invention pertains in general to the transmission of programs and specifically relates to such systems for transmitting programs in auditory perspective.

5 The principal object of the invention comprises providing a system having means for simultaneously transmitting a plurality of program signals and an arrangement for utilizing such program signals for producing binaural effects. This system is particularly adapted for the transmission of programs by wired radio facilities in which programs are transmitted at discrete modulated carrier frequencies over wire networks.

15 A further object of the invention consists in producing a transmission and reception system for multiple binaural program channels.

20 A further object of the invention comprises providing a multi-channel broadcasting system including an arrangement for selectively utilizing such channels in desired combinations for program transmission purposes.

25 These and other objects will be apparent from the following, reference being made to the accompanying drawings in which like reference numerals designate corresponding parts and in which:

30 Fig. 1 is a schematic representation of transmission equipment provided in accordance with one embodiment of the invention;

35 Fig. 2 is a schematic representation of receiving equipment for cooperation with the transmission equipment of Fig. 1; and

Fig. 3 is a graphical representation of typical frequency conditions in the operation of the system.

40 The invention contemplates the provision of a program distribution system in which binaural programs are made available to subscribers. It is one of the features of the invention that subscribers of different classes may be served for receiving either mon-aural "straight" programs without auditory perspective or binaural programs having auditory perspective. That is, various subscribers served by the same transmission network are adapted in different senses to receive differently characterized programs. Further, the system of the invention provides a system whereby the program channels can be selectively connected with different studios or modulation sources for adapting the program channels individually to either mon-aural program broadcasting or program broadcasting in auditory perspective for binaural purposes.

45 Referring to the drawings in detail and particularly to Fig. 1, a transmission network 1 is

represented as extending into power substation 2. In the present embodiment of the invention, the power lines of the network 1 are of the three phase type for delivering carrier alternating current from the power equipment shown. In this embodiment of the invention, the system will be described as operating over commercial power lines in accordance with wired radio practice, although other transmission arrangements utilizing independent wire lines and the like may be utilized if desired. The power substation 2 includes carrier frequency equipment comprising a master oscillator 3 which operates into a harmonic generator and amplifier 4. The master oscillator 3 provides sustained carrier frequency oscillations 10 to the unit 4 which produces harmonically related discrete carrier frequencies in amplified form which are delivered over a circuit to the individual transmitters 5—9 which are respectively utilized for transmitting program channels A—E. 15 Each of these transmitters operates through associated filters 10—14 which in turn operate through capacity couplings into the power network feeder lines 1. The transmitters 5—9 include known equipment for producing modulated polyphase carrier frequency energy. All of the filters 10—14 are of the band pass type for limiting the transmission output of the associated transmitters to discrete program channels such as represented by the channels a—e shown in Fig. 3. 20 The representation of Fig. 3 illustrates the relation of these program channels along the frequency spectrum.

25 The program studio 16 includes studios 17—21 corresponding to program channels A—E. Each 30 of the studios includes a suitable pick-up such as a microphone and amplifier controlled thereby. These studios are associated with the transmission of programs which are not of the auditory perspective type. The program studio 16 also 35 includes studio 23 and studio 24, respectively designated as studio "A—A" and studio "B—B". These two studios are for transmitting programs in auditory perspective and each includes microphones 25 and 26 operating into amplifiers 27 40 and 28. The microphones 25 and 26 in each studio are positioned in physical displacement, such as upon opposite sides of a stage, for collectively picking up sound waves in auditory perspective.

45 It will be understood that the studios 17—21 as well as studios 23 and 24, and the arrangement and number of pick-up systems therefor are an illustration of a typical form of the invention 50

and that various arrangements can be utilized if desired.

The output circuits from the amplifiers of the studios 17 and 18 are connected to a switching system 30 while the output circuits from amplifiers of studios 19 and 20 are connected to the switching system 31. Further, connections from the output circuits of studios 17-20, as well as a connection from studio 21, are provided to the 10 individual terminals of selector switch 32. The output circuits from amplifiers 27 and 28 of studio 23 are connected with switching system 30 while the output circuits from amplifiers 27 and 28 of studio 24 are connected with switching 15 system 31. In the right-hand position of switching system 30, amplifiers 27 and 28 of studio 23 are respectively connected with transmitters 5 and 6, while in the right hand position of switching system 31 the amplifiers of studio 24 are 20 respectively connected with transmitters 7 and 8. In the left hand position of switching system 30 the amplifiers of studios 17 and 18 are respectively connected with transmitters 5 and 6. In the left hand position of switching system 31 the 25 amplifiers of studios 19 and 20 are respectively connected with transmitters 7 and 8. The selector switch 32 may be operated to connect any one of the studios 17-21 with the transmitter 9. It will be seen, in this arrangement, that the 30 studios 17-21 can be individually utilized to control transmitters 5-9. On the other hand, studio 23 may operate through transmitters A and B to transmit the same program divided into auditory components individually transmitted 35 by transmitters 5 and 6, while studio 24 may operate in a similar manner to transmit the auditory perspective components of a program by transmitters 7 and 8.

Consideration will now be given to the reception 40 of programs in accordance with the invention. As shown in Fig. 2, the lines 1 are provided with a plurality of transformers 40 and 41. These transformers are of the usual step-down type for providing consumers' voltages of alternating current from the high tension feeder lines 1. The transformers 40 and 41 are respectively connected with consumers' secondary distribution circuits 42 and 43. The usual service equipment, including master switch, fuse panel, 50 and watt-hour meter, is not shown.

The distribution circuit 42, representative of the consumer's house circuit, is provided with equipment for the reception of binaural programs whereas the distribution circuit 43, representative 55 of another consumer's house circuit, is provided with equipment for the reception of straight programs without auditory perspective. The distribution circuit 42, in addition to connections with the usual power consuming equipment, is provided with power connections to 60 wired radio receivers 45 and 46. These receivers also include signalling connections through auxiliary wire lines 47 and 48 capacitively coupled with the distribution circuit 42. Such 65 circuits are adapted for the special reception of signalling energy and may extend to connecting points at various other portions of the secondary circuit. For example, these special circuits may be connected to the commercial high tension side of 70 the step-down transformer 40. The receivers 45 and 46 are provided with translating devices such as loud speaking units 49 and 50. These units are spatially positioned within the consumer's dwelling in correspondence with the 75

spatial position of the microphones 25 and 26 in the studios 23 and 24.

Receivers 45, 46, and 53 are adapted to receive frequencies as represented by curves "a" to "e". To produce the auditory perspective or binaural effect, receivers 45 and 46 at any one time are paired to individually receive signals respectively within different ones of the frequency bands represented by curves "a" to "c". For example, receiver 43 would receive band "a" while receiver 46 would receive "b", or receiver 46 may be adjusted to receive band "d". A unitary control knob 51 is connected with the operable parts of the selection circuits in receivers 45 and 46 so that after proper adjustment a simultaneous selection can be made between these two paired selection conditions. Thus the consumer may selectively receive binaural programs, the auditory perspective components for each program being individually reproduced by the loud speaking units 49 and 50, respectively spatially positioned in the consumer's dwelling in correspondence with the position of the microphone units in the studios.

The consumer's distribution circuit 43 includes power connections to a wired radio receiver 53 having a single input circuit 54. This receiver 53 is provided with a loud speaking unit 55. The frequency selection circuits of the receiver 53 are adjusted to render the receiver responsive to a program within the frequency bands represented by the curves "a1", "c1", or "e1", of Fig. 3, these curves corresponding to the ranges represented by the curves "a", "c", and "e". The receiver 53 is therefore not of the binaural type 35 and is adapted for the reception of straight programs. However, since the selection circuits of the receiver 53 are adjustable to but one of the auditory perspective component channels of each of the binaural ranges, there is no evidence at 40 the receiver to lead the consumer to any annoying duplication of programs in changing from one channel to the other such as might take place if he were able to receive both channels "a" and "b" and both channels "c" and "d". Obviously 45 by not using either of receivers 45 or 46 simultaneously with its companion receiver, the remaining receiver will give mon-aural reception.

It will be apparent from the foregoing that the system of my invention provides for the transmission and reception of wired radio programs in which means are provided for enabling various consumers of different classifications to receive "straight" or mon-aural programs and binaural programs to produce auditory perspective. Although I have shown a preferred embodiment of my system, it will be obvious that various changes can be made therein without departing from the intended scope of my invention.

I do not, therefore, desire to limit myself to the foregoing except as may be pointed out in the appended claims.

What I claim as new and desire to secure by Letters Patent of the United States is:

1. An electrical transmission system comprising, a transmission medium comprising a commercial power network, means for transmitting over said medium a plurality of channels comprising modulated discrete frequency bands, program means including at least two pick-up devices spatially positioned with respect to each other for picking up waves respectively in different auditory aspects, said pick-up devices operating to individually operate through said channels, and a plurality of receiving stations 75

operatively associated with said medium for the selective reception of carrier frequencies transmitted thereover, one of said receiving stations being provided with a plurality of receiving means for simultaneously receiving from said different channels, and translating units respectively connected with said receiving means and spatially positioned in correspondence with the position of said pick-up devices, and another of said receiving stations being provided with receiving means for the reception at any one time of signals transmitted over said medium through one of said channels, said receiving means including power operated devices and connections from said network for supplying commercial power as well as signalling energy to said means.

2. An electrical transmission system comprising, a transmission medium, means for transmitting over said medium a plurality of channels comprising modulated discrete frequency bands, program means including at least two pick-up devices spatially positioned with respect to each other for picking up waves respectively in different auditory aspects for producing a plurality of programs each comprising at least two program components individually transmitted through said channels, said pick-up devices operating to individually operate through said channels, and a plurality of receiving stations operatively associated with said medium for the selective reception of carrier frequencies transmitted thereover, one of said receiving stations being provided with a plurality of receiving means for simultaneously receiving from said different channels, and translating units respectively connected with said receiving means and spatially positioned in correspondence with the position of said pick-up devices, and another of said receiving stations being provided with receiving means for the reception at any one time of signals transmitted over said medium through one of said channels, said last mentioned receiving means being operative to select between programs but not between said program components in the reception of signalling energy from said channels.

3. An electrical transmission system comprising, a transmission medium comprising a com-

mercial power network, means for transmitting over said medium a plurality of channels comprising modulated discrete frequency bands, program means including at least two pick-up devices spatially positioned with respect to each other for picking up waves respectively in different auditory aspects, said pick-up devices operating to individually operate through said channels, and a plurality of receiving stations operatively associated with said medium for the selective reception of carrier frequencies transmitted thereover, one of said receiving stations being provided with a plurality of receiving means for simultaneously receiving from said different channels, and translating units respectively connected with said receiving means and spatially positioned in correspondence with the position of said pick-up devices, and another of said receiving stations being provided with receiving means for the reception at any one time of signals transmitted over said medium through one of said channels, said receiving means including power operated devices, and including both power and signalling connections from said network to said receiving means.

4. An electrical transmission system comprising, a transmission medium, means for transmitting over said medium a plurality of channels of discrete carrier frequencies, program means for picking up program waves in auditory perspective from different program sources and including a plurality of sets of wave pick-up devices each pick-up device operating through one of said channels, and each set of pick-up devices operating to transmit the auditory perspective components of a particular program, receiving means coupled with said medium and comprising plural organizations each for respectively receiving one of the components corresponding to any one of the programs, translating means, and selection control means for controlling said organizations to conjointly deliver to said translating means the separate components of a particular program of any one of several programs transmitted over said medium.
